UNITED STATES PATENT OFFICE.

FRANCIS LEONARD STREET, OF NEODESHA, KANSAS, ASSIGNOR OF ONE-HALF TO EDWIN L. FAY, OF SPRINGFIELD, MISSOURI.

LOW-PRESSURE ALARM.

SPECIFICATION forming part of Letters Patent No. 511,818, dated January 2, 1894.
Application filed July 22, 1891. Serial No. 400,300. (No model.)

To all whom it may concern:

Be it known that I, FRANCIS LEONARD STREET, a citizen of the United States, residing at Neodesha, in the county of Wilson and State of Kansas, have invented certain new and useful Improvements in Low-Pressure Alarms for Air-Brake Systems; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to fluid pressure railway brakes, especially to those operated by compressed air.

For the sake of simplicity, I shall describe my invention as applied to the well-known 20 Westinghouse system, though it is adapted for use with other systems.

An essential feature of the Westinghouse automatic brake system is the maintenance in the train pipes of a predetermined air pressure. The train pipe is in connection through the triple valves with the auxiliary reservoirs under the cars, so that the pressure in the train pipe and reservoirs is the same. When the train pipe pressure is suddenly reduced, 25 either accidentally or intentionally, the triple valves operate to admit the air from the reservoirs into the brake cylinders and apply the brakes; but if the reduction of pressure in the train pipe takes place very gradually, 30 as by reason of slight leaks in the pipes and couplings, the triple valves will not be moved, and the pressure falls in the auxiliary reservoirs simultaneously with that in the train pipe. It is usually found necessary to keep 35 the air pump running slowly all the time to make up for the unavoidable leakage. If the feed valve in the engineer's valve gets stuck, or if the pump fails to operate properly, the supply of air to the train pipe ceases, and the 40 reduction in pressure due to leakage may become so great as to render the brakes useless. It is customary to connect a pressure gage with the train pipe in the cab of the locomotive, so that the engineer can ascertain at 45 any time the condition of his "air;" but it frequently happens that the necessity of watching the track, looking out for signals, and other imperative duties, so engross his attention that the engineer sometimes forgets to look at his air gage.

The object of my invention is to give an audible warning when the pressure in the train pipe reaches a dangerously low point.

To this end my invention consists in providing a suitable outlet from the train pipe, 5 having a valve which is held normally closed by the air pressure, but which opens automatically when the pressure falls below a predetermined point, and admits the air to a whistle, or the like. The air may exert its 55 pressure either directly upon the valve, or upon a piston or diaphragm attached thereto.

In the drawings Figure 1 is a longitudinal section of my alarm, and a portion of the engineer's valve. Fig. 2 is a bottom plan view 60 of the valve proper. Fig. 3 is a diagrammatic plan of the valve and alarm.

The engineer's valve proper, A, is made as usual, with the addition of a small radial recess *a* cut in the outer wall of the cavity *a'*. 65 When the handle is in the running position, as shown in Fig. 3, this recess registers with a small hole *b* drilled down into the valve seat, and connecting at its lower end with a lateral hole *b'* drilled in from outside of the 70 valve body B. These holes in connection with the recess *a* form a passage for the air from the train pipe to the atmosphere when the valve is in the position for running, since the cavity *a'* laps over the direct application supply port, as shown in Fig. 3, and said port is always in communication with the train pipe. The hole *b'* is tapped to receive the threaded 75 end of the valve casing C, or a pipe leading thereto. Said casing consists preferably of a 80 tube, counterbored to form a central chamber, the outer end of which is threaded internally to receive an adjusting screw D, which has a milled head *d*, and is locked by a jam nut *D'*. A valve E is seated against the inner end of the casing, its stem *e*, which is 85 preferably squared, grooved or ribbed, projecting into the central chamber, in which a helical spring F is located, compressed between the end of said stem and the screw D. 90

and e' , fixed in the stem e , plays in a slot in the casing to limit the movement of the valve. The screw D is tubular, and attached to its head d is a whistle G of any suitable construction. The one shown consists of two leave disks united at their edges, each having a central perforation.

The operation of my device is as follows: the spring F is adjusted to force the valve E open against the air pressure in the holes b when said pressure falls below, say, forty pounds. The air then flows out through the casing and tubular screw to the whistle, giving an audible alarm, which continues until the engineer again establishes the normal pressure in the train pipe. Should he neglect to do this, the air will escape rapidly enough through the alarm to soon set the rakes gently, and eventually stop the train. The device is thus an efficient safeguard even if the whistle fails to sound.

The alarm may be located at the point X or instead of at the place shown: in fact, it may be placed anywhere in connection with the train or small reservoir pipes. When arranged as illustrated in the drawings, the whistle will cease to sound the instant the handle H is moved away from the running position, since the recess a will thereby be thrown out of coincidence with the hole b . When the alarm is at the point X or Y it will continue to sound until the pressure in the train pipe is restored to the normal.

My alarm is simple in construction, and costs but little. It can be easily applied to the engineer's valve, and does not interfere with the proper operation of said valve.

The details of construction may be considerably varied without departing from the spirit of my invention. The necessity for such a device, and the success of my invention in meeting the need, have been fully demonstrated by me in practice.

Having thus described my invention, what I claim, and desire to secure by Letters Patent, is—

1. A low pressure alarm for automatic air brake systems, consisting of a valve controlling an outlet from the train pipe, an audible alarm communicating with said outlet, and a spring for opening said valve when the train pipe pressure falls below a predetermined point, said outlet communicating continuously with the entire train pipe as long as

the valve remains open, substantially as described.

2. A low pressure alarm for automatic air brake systems, consisting of a valve controlling an outlet from the train pipe, a spring arranged to open said valve when the air pressure falls to a given point in the train pipe, and a whistle adapted to be sounded by the escaping air, said outlet communicating continuously with the entire train pipe so long as the valve remains open, substantially as described.

3. The combination with an engineer's valve having the cavity a' and a passage leading from said cavity to the atmosphere, when the engineer's valve is in the running position of a valve controlling said passage, a whistle communicating with said passage and a spring adapted to open the valve and permit the air to escape when the train pipe pressure falls below a predetermined point, substantially as described.

4. The combination with an engineer's valve having the cavity a' and a recess a at one side thereof, and provided with a passage leading to the atmosphere and adapted to register with the recess a when the valve handle is in the running position, of a valve controlling said passage, a whistle communicating with said passage and a spring adapted to open said valve when the train pipe pressure falls below a given point, substantially as described.

5. A low pressure alarm for automatic air brake systems, consisting of the casing C , the valve E seating against the end of the casing, the tubular screw D , an audible alarm communicating with said tubular screw and the spring F , arranged between the valve stem and the screw and adapted to force the valve away from its seat, substantially as described.

6. The combination with the casing C of the valve E seating against the end of the casing and having a stem e , the tubular screw D , the spring F between the screw and the valve stem, and the whistle G attached to the outer end of the screw substantially as described.

In testimony whereof I affix my signature in presence of two witnesses.

FRANCIS LEONARD STREET.
